United States Patent Office

Des. 212,569
Patented Oct. 29, 1968

212,569

URINAL

Richard Gelak, Cherry Hill, N.J., and Ralph Ippoliti, Philadelphia, Pa., assignors to Herbert A. Segal, Philadelphia, Pa.

Filed Aug. 18, 1967, Ser. No. 8,320

Term of patent 14 years

(Cl. D83—1)

FIG. 1

FIG. 2

FIG. 5

FIG. 3

FIG. 4

FIG. 6

FIGURE 1 is a front perspective view showing our new design;

FIGURE 2 is a side view thereof;

FIGURE 3 is a top plan view thereof;

FIGURE 4 is a bottom plan view thereof;

FIGURE 5 is a front elevation view thereof; and

FIGURE 6 is a rear elevation view thereof.

The dominant features of our invention reside in the portions shown in full lines.

We claim:

The ornamental design for a urinal, substantially as shown and described.
